UNITED STATES PATENT OFFICE.

CHARLES A. THOMPSON, OF NEW YORK, N. Y.

APPARATUS FOR DUPLICATING MANUSCRIPT, &c.

SPECIFICATION forming part of Letters Patent No. 398,471, dated February 26, 1889.

Application filed August 6, 1887. Serial No. 246,275. (No model.)

To all whom it may concern:

Be it known that I, CHARLES A. THOMPSON, of the city, county, and State of New York, have invented certain new and useful Improvements in Apparatus for Duplicating Manuscript, &c.; and I do hereby declare that the following is a full, clear, and exact description of the invention, which will enable others skilled in the art to which it appertains to make and use the same.

Figure 1 is a side elevation, and Fig. 2 a longitudinal sectional view taken in the line xx of Fig. 3, of an apparatus embracing my said invention. Fig. 3 is a plan or top view 15 of the same.

This invention is designed for duplicating or multiplying written copies of manuscript or other matter. The matter to be copied is provided upon a roller, A, preferably by placing upon said roller a sheet of paper or other material having upon it in reverse and in an aniline or other suitable copying-ink the matter to be copied. Parallel to this roller A is a roller, B, which serves to press the duplicate sheet upon which the matter is to be copied against the surface of the roller A, or, to speak more exactly, upon the surface provided in reverse to be copied. A series of endless aprons or tapes, C, will carry the secondary or duplicate sheet inward between the said rolls. Motion is given to these tapes by a band-wheel, a' , band b' , and pulley c' from the shaft of a secondary roll, E, interposed in front of the rolls A B, and arranged to impel 25 and guide the sheet between said rolls A B. The inner end of the table D is provided with vertical slots c , through which play vertical moving studs or stops d , which are formed upon the ends of rods or levers G, which are 30 attached to a rock-shaft, H, the said rock-shaft having at its end the crank f , to which a connecting rod or pitman, m , is pivoted, the other end of which is movably attached to an eccentric or cam, n , on the shaft of the roll 35 A. A spring, g , is arranged to press the rods or levers G upward to thrust the studs d up through the slots or openings c . When these studs are thus thrust upward, they provide stops which prevent the secondary sheet— 40 that is to say, the sheet upon which a duplicate copy is to be formed—from passing to the

rolls A B, &c.; but when the roll A is brought to such position that the first line or series of characters to be copied will come upon the desired place upon the secondary or duplicate sheet the eccentric or cam n , acting through the rod or pitman m , will actuate the crank f to depress the studs d , and thereby permit the motion of the endless aprons or tapes to convey the duplicate sheet to and between the rolls A B; so it receives by thus passing between the rolls the printing or impression from the printed or reversed matter on the roll A.

I is a transverse trough filled with felt or other porous material, and having a longitudinal slot or a series of openings in its bottom, through which water may pass to a porous pad, K, attached beneath said bottom. This trough is supported at each end by swinging bars L.

One or both ends of the shaft of the roll A is provided with a cam, N, so arranged that at a suitable point in the rotation of the roll A the trough will be raised and afterward lowered. Water or other suitable liquid for moistening the paper as it passes to the rolls A B is placed in the trough I.

A trough, B', for containing water is supported at the inner end of the table beneath the said trough I and its contained moistening-pad K, and beneath the track or plane of the paper, and serves to moisten the under side of the paper, which will be depressed into the water in said trough B' by the descending movement of the upper trough and its pad.

As the secondary or duplicate sheet is fed forward to and between the rolls A B, as hereinbefore explained, it passes underneath the pad K of the trough I, and the latter, being moistened from water contained in said trough, wets the paper to the requisite degree, the trough being of course depressed during this operation.

The object of temporarily lifting the trough is to enable the head of the secondary or duplicate sheet—as, for example, a letter-head—to pass to the rolls A B without being wet, the parts of the apparatus being so constructed, arranged, and provided in relation with each other that the trough is lifted when the head of the sheet passes underneath the same, and

is caused to descend at such part of the sheet at which it is designed the copying shall begin.

What I claim as my invention is—

5 1. The combination of the roller for containing the matter to be copied, the pressure-roller B, the feeding-table, and a vertically-movable water-retaining wetting device for moistening the paper arranged above the 10 plane of the table and having a movement below such plane, substantially as described.

15 2. The combination of the roller A, for carrying the matter to be copied, the pressure-roller B, the secondary feeding and guiding 20 roller E, table D, and a wetting device for moistening the paper, all substantially as and for the purpose herein set forth.

25 3. The combination of the roller A, for carrying the matter to be copied, the pressure-roller B, a table, D, a wetting device, and movable stops d, for intermitting the movement of 30 the paper from the table to the wetting device and the rollers A B, all substantially as and for the purpose herein set forth.

35 4. The combination of the roller A, for carrying the matter to be copied, the pressure-roller B, the secondary feeding and guiding roller E, a table, D, a wetting device, and movable stops d, for intermitting the movement of 40 the paper from the table to the wetting device and the rollers A B, all substantially as and for the purpose herein set forth.

45 5. The combination of the roller A, for carrying the matter to be copied, the pressure-roller B, table D, a movable wetting-trough and pad, and mechanical devices for giving an intermittent vertical movement thereto, all substantially as and for the purpose herein set forth.

50 6. The combination of the roller A, for carrying the matter to be copied, the pressure-roller B, table D, a movable wetting device, and bars L and cam N, for giving an intermittent vertical movement thereto, all substantially as and for the purpose herein set forth.

55 7. The combination of the roller A, for carrying the matter to be copied, the pressure-roller B, the trough B', for containing the 60 moistening-liquid, and a movable device constructed and arranged to force downward the paper as it passes to the rolls A B into the said trough, all substantially as and for the purpose herein set forth.

8. The combination of the roller for carrying the matter to be copied, the pressure-roller B, the trough B', for containing the moistening-liquid, and the movable upper moistening-trough, I, having a dampening-pad, K, and means for intermittently forcing 65 said upper trough and its pad downward, carrying with it the paper to receive the copy into the said trough B', substantially as and for the purpose specified.

9. The combination of the roller for containing the matter to be copied, the pressure-roller, and a feeding-table for the paper to receive the copy, with a trough for containing water having a fixed relation to and arranged beneath the end of said table, a vertically-intermittently-movable trough, I, containing a moistening-pad arranged above the plane of said table, and vertically-intermittently-movable stops d, operating beneath the plane of said table, substantially as described, for the 70 purpose specified.

10. The combination of the roller for carrying the matter to be copied, the pressure-roller B, and a feeding-table for the paper to receive the copy, with a wetting device consisting of a fixed and an intermittently-movable trough part arranged, respectively, below and above the plane of the table and the track of the paper to receive the copy, the movable part being operated to depress said paper below the plane of the table, substantially as 75 described.

11. The combination of the roller for containing the matter to be copied, the pressure-roller B, and a feeding-table for the paper to receive the copy, with a wetting device consisting of a fixed and an intermittently-movable trough part arranged, respectively, below and above the plane of the table and the track of the paper to receive the copy, vertically- 80 movable stops arranged below the table, mechanical devices for giving an intermittent downward movement to the movable wetting part upon the said paper, and mechanical devices for giving an intermittent upward movement to the stops upon said paper to raise it when the movable wetting part is raised free of the latter, substantially as described, for the 85 purpose specified.

CHARLES A. THOMPSON.
